UNITED STATES PATENT OFFICE.

JOSIAH BYRAM MILLET, OF BOSTON, MASSACHUSETTS.

SUBMARINE SIGNALING.

SPECIFICATION forming part of Letters Patent No. 769,100, dated August 30, 1904.

Application filed July 20, 1903. Serial No. 166,252. (No model.)

To all whom it may concern:

Be it known that I, JOSIAH BYRAM MILLET, a citizen of the United States, residing at Boston, in the county of Suffolk and State of Massachusetts, have invented a new and useful Improvement in Submarine Signaling, of which the following is a full, clear, and exact description, reference being had to the accompanying drawings, forming a part of this specification, 10 in explaining its nature.

The invention comprises means whereby a vessel may be employed to indicate its position and direction of movement to an observer at some distance away.

15 It consists in combining with the vessel two devices or instruments for creating sound impulses or waves, so located in the vessel as to communicate such impulses or waves to the water surrounding the vessel and in a manner

20 to permit the water to conduct such sound impulses or waves and also in a manner to permit the vessel or a portion of it to operate to vary the value of the sound-waves, so that the observer may be able to discern by the

25 differences in value of the sound-waves received through the water by him which side or part of the vessel is turned or points toward him and in what direction the vessel is moving from the time when the signals are first received by him.

I prefer to employ for creating sound impulses bells adapted when struck to deliver a note the fundamental of which shall be sharp in pitch, as I believe notes having high vibration

35 communicate to the water more effective sound-waves than those of relatively low vibration. I prefer also that the sound-producing devices be placed opposite each other in the boat and preferably near the bow thereof

40 in order that a movement of the boat shall form the sound-shadow which is the means by which the differences in values of the different devices is caused.

I will now describe the invention in conjunction with the drawings forming a part 45 of this specification, wherein—

Figure 1 is a diagrammatic view representing three positions of the ship with respect to an observer, the signaling devices being represented in the bow of the ship. Fig. 2 is a

view showing three positions of the ship, the signaling devices being shown in the stern of the ship. Fig. 3 is a view showing two positions of the ship and the use of one signaling device near the bow.

55

Referring to the drawings, A represents the vessel.

B represents one of the devices for producing sound-signals in the water mounted therein at one side thereof, preferably near the stern, and B' represents the other means for producing sound-signals in the water mounted upon the other side thereof, preferably opposite the first. Any sound-producing device operated in any desired way may be used for this purpose. I prefer to use a bell which has a note the fundamental of which is of a rather sharp or high pitch, and I also prefer that the bells be rung automatically, although this is not an essential. Any of the devices 65 employed in the various patents of Elisha Gray and Arthur J. Mundy for producing sound-vibrations in water or described in their applications may be used, and any other location of the sound-producing devices in the 70 vessel which will enable the results of the invention to be attained may be substituted for the one shown and described. Even one signal-producing device will answer when it is so located that the vessel itself may be used 75 as a means of producing a sound-shadow on its sound-waves for the purpose of varying to the observer the effect or value thereof.

I do not limit the invention to the employment as a means for producing sound-signals 80 of a bell, but may use any instrumentality which is capable of producing sound-vibrations adapted to be transmitted by water and to be carried by a vessel. Neither do I confine myself to the number of devices for producing sound-signals employed in the ship or to their location with respect to the sides of the ship, so long as the ship itself is used as a means for determining the respective values of the sound-signals.

95

Having thus fully described my invention, I claim and desire to secure by Letters Patent of the United States—

1. The method of communicating information as to the position or direction of a mov-

100

- ing vessel to an observer removed from the vessel, consisting of the employment of the vessel itself, in connection with devices upon the vessel for producing sound vibrations or waves in the water surrounding the vessel, and the turning of the vessel for varying the degree or value of said sound waves or vibrations in a given direction.
2. In a method of communicating information as to the position or direction of a moving vessel to an observer removed from the vessel, the employment upon the vessel of two devices for producing sound waves or vibrations in the water surrounding the vessel, and the turning of the vessel to cause the same to act as a sound-reflector for varying the relative values or intensities in a given direction,

of the sound waves or vibrations from such devices.

3. The method of communicating information as to the position or direction of the moving vessel to an observer removed from the vessel, consisting of the employment of the vessel itself, in connection with a device located toward the end of the vessel for producing sound vibrations or waves in the water surrounding the vessel, and the turning of the vessel for varying the degree of value of said sound waves or vibrations in a given direction. 20 25

JOSIAH BYRAM MILLET.
In presence of—

J. W. DOLAN,
SAUL SIPPERSTEIN.
